UNITED STATES PATENT OFFICE.

FREDERICK HAUFF, OF AKRON, OHIO, ASSIGNOR OF ONE-HALF TO JEFFERSON D. SLATER, OF AKRON, OHIO.

INFLATED TOY.

Application filed May 22, 1928. Serial No. 279,749.

This invention relates to toys and more particularly to an inflated toy and method of forming the same.

One object of the invention is to provide a toy formed from an elongated sack of sheet rubber which by proper folding of its closed end portion may be caused to define a head and body portion of a figure when inflated.

Another object of the invention is to so 10 fold the elastic sack when forming the head that a flap will be provided between the head and body portion and prevent the head from being inflated beyond a desired extent when air is forced into the body through the open 15 end of the sack and thereby cause the head to be properly proportioned with respect to the inflated body.

Another object of the invention is to provide a toy of the inflated type which may be 20 supported in a natural position by legs adhering to the under portion of the body and may have its head and body painted or otherwise marked to simulate a bird or animal and also to provide the head with a representation of a bill in case the toy constitutes 25 a representation of a duck or other bird.

Another object of the invention is to allow the body to be easily inflated and air retained therein by a simple manipulation of 30 the open end portion of the sack.

The invention is illustrated in the accompanying drawing, wherein

Figure 1 is a perspective view of an inflated toy representing a duck and constructed in accordance with this invention;

Fig. 2 is a side elevation of the sack from which the inflated toy is formed, and

Fig. 3 is a vertical longitudinal sectional view through the toy.

The inflated toy constituting the subject-matter of this invention has been illustrated in the form of a duck, but it will be understood that it could represent any other bird desired or could be marked to represent an animal. When making the toy, a sack 1 of thin rubber is first formed by dipping a properly shaped core in liquid rubber and allowing the rubber to dry upon the core. After the rubber has dried, it is stripped 45 from the core or it can be again dipped and allowed to dry if the first dipping does not produce a sufficient thickness of rubber. The sack is of a tubular shape throughout the greater portion of its length but has its 50 closed end portion enlarged, as shown at 2,

and this enlarged portion is oval in shape and tapers towards the tubular portion. After the sack has been formed upon its mold or core and removed therefrom, it is 60 folded in slightly spaced relation to the inner end of the enlarged end portion 2 to provide a head 3 having a depending neck 4 which merges into the body 5. The surfaces which contact when the sack is folded are 65 secured to each other by cement or liquid rubber which when set will firmly connect them and the adhering portions of the sack provide a wall or flap 6 which extends between the head and body portion of the toy but is free at its forward end. By this ar- 70

angement a certain amount of air may enter the head when air is forced into the body through its open rear end but the flap or wall will be pressed forwardly as soon as a certain amount of pressure is exerted by air 75

forced into the body and, therefore, the head may only be inflated a small extent. A wing 7 is painted or otherwise marked upon each side of the body and each side of the head has an eye 8 marked thereon but it will be 80

obvious that the entire body and head may be marked to define feathers if so desired. The bill 9 which projects forwardly from the head consists of a flat sheet of cardboard or any other suitable material cut the proper 85

shape and having its rear end cemented or otherwise secured to the head so that it projects forwardly from the head in its natural position. There has also been provided feet and legs consisting of disks 10 and short 90

rods 11 which have their lower ends glued to the disks and their upper ends cemented to the body portion against the under surface thereof. The flat disks provide very good supports to retain the figure in an upright 95

position when inflated and in addition provide a very good representation of the webbed feet of a duck. In order to allow the toy to be easily inflated, there has been provided a nipple 12 which is preferably formed 100

of wood, and this nipple is fitted upon the rear end portion of the sack and this open end rear portion then rolled back about the nipple, as shown at 13. Therefore, the nipple will be firmly held in place.

When the toy is in use, the nipple is placed in the mouth and the air forced through the open end of the sack to inflate the body and head. A small amount of air passes into the head and the flap 6 is then pressed for- 110

wardly by air pressure until it assumes the position shown in Fig. 3. As additional air is forced into the sack, the body will be inflated and the extent to which it is inflated may be controlled by the quantity of air forced into it. After the body has been inflated as much as desired, a turning motion is imparted to it while the tongue is held over the open end of the sack and this will cause it to be 10 twisted, as shown at 14, and very effectively prevent the air from escaping. Since the twisted portion of the sack will be disposed within the nipple and a frictional binding will take place between the nipple and the 15 sheet rubber from which the sack is formed, air will be retained in the body and the duck may be supported upon its feet, as shown in Fig. 1. While it is stated that the rear end portion is twisted to retain the air in the 20 body, it will be obvious that the nipple could be placed within the open end of the sack and a suitable valve provided in the nipple to retain the air in the body until released or gradually allowed to pass outwardly through the 25 nipple.

Having thus described the invention, I claim:

1. A method of forming an inflatable toy figure consisting of forming a bag open at one 30 end and closed at its other end, folding one end portion of the bag towards its other end and joining contacting portions to divide the bag into head and body forming portions, attaching supports to the body forming portion, and applying at the open end of the bag an element serving to allow the body and head to be inflated and air retained therein.

2. A method of forming an inflatable toy figure consisting of forming a bag open at one 40 end and having its closed end portion enlarged, folding the bag adjacent the enlarged end portion and cementing contacting portions of the bag to form a head of the enlarged end portion and a body of the remainder of the bag, marking the head and body to define eyes and wings, applying a bill to the head and supporting legs to the body, and fitting into the open end of the bag an inflating and air retaining nipple.

3. An inflatable toy figure comprising a 50 sack of elastic material open at one end and having its closed end portion enlarged, the sack being folded adjacent its enlarged end portion to provide contacting portions, the 55 said contacting portions being adherently secured to each other to provide a body and head and a flap between the same, and means at the open end of the sack to facilitate inflation thereof and effect retention of air in the 60 same.

4. An inflatable toy figure comprising a

body open at one end, a head at the other end of the body communicating therewith, a wall between the body and head having one end free and serving to permit limited inflation 65 of the head, and means at the open end of the body to facilitate inflation thereof and effect retention of air in the same.

5. An inflatable toy figure comprising a 70 body open at one end, a head at the other end of the body communicating therewith, a wall between the body and head having one end free and serving to permit limited inflation 75 of the head, a bill carried by said head, legs carried by said body and having supporting feet, the head and body being marked to define eyes and wings, and a nipple in the open end of the sack to facilitate inflation thereof and constituting means to retain the open end portion twisted after inflation to retain air in the body.

6. An inflatable toy figure comprising a 80 sack of elastic material open at one end and closed at its other end, the said sack being folded in spaced relation to its closed end to 85 provide contacting portions, the said portions being adherently secured to each other to provide a body and head and a flap between the same serving to permit limited inflation of the head when the body is inflated.

7. A method of forming an inflatable toy figure consisting of forming a bag open at one end and closed at its other end, and folding the bag intermediate its ends to provide contacting portions, and securing the contacting portions together to divide the bag into head and body forming portions having a 90 wall between them free at one edge and serving to permit limited inflation of the head when the body is inflated.

8. A method of forming an inflatable toy figure consisting of forming an elastic container having an inflating opening, folding the container in spaced relation to its opening to provide contacting portions, and securing the contacting portions together to divide the container into head and body forming portions having a wall between them free along one edge and serving to permit limited inflation of the head when the body is inflated.

9. An inflatable toy figure comprising a 100 sack of elastic material having an inflating opening and having a closed end portion folded upon itself to provide contacting wall portions, the said wall portions being secured together to provide a body and head and a flap between the same serving to limit inflation of the head when the body is inflated.

In testimony whereof I affix my signature. 110

FREDERICK HAUFF. [L.S.]
